FEEDING MECHANISM

Albert H. Weis, Nyack, N. Y., assignor to Willcox
& Gibbs Sewing Machine Company, New York,
N. Y., a corporation of New York

Application May 17, 1940, Serial No. 335,713

17 Claims. (Cl. 112—214)

This invention relates to sewing machines and more especially to an improved feeding mechanism particularly adapted to be associated with a sewing mechanism to supplement the action of the regular feeding mechanism thereof.

In Patent 1,736,297 granted to John P. Weis on November 19, 1929, there is shown an auxiliary or supplemental feeding mechanism of the same general type as the one forming the subject matter of the present invention, and adapted to pull material away from or relative to a sewing machine associated therewith.

The need for a puller feed mechanism to supplement the regular sewing machine feed in the stitching of certain types of articles and materials is well known. Thus with certain heavier materials the puller feed mechanism serves to relieve some of the strain on the sewing machine feeding mechanism and to assist in the production of uniform lengths of stitches and of smoothly stitched seams free from puckers. In the sewing of certain finer materials, wherein the puller feed is not used, there is a tendency to slightly draw up the stitches, thus causing minute puckers as the stitch ties into the work because of the excess tension of the threads. When a puller feed is used this adverse tendency is overcome as the puller feed acts across a rather large portion of the work, exerting a uniform pull in unison with the movement of the regular feed dog of the sewing machine to prevent such puckers.

It is an object of the present invention to provide an auxiliary or supplemental feeding device of the same general character as the one shown in Patent 1,736,297, but which is more positive in its action, has a novel and advantageous driving mechanism, and which is capable of an advantageous adjustment particularly helpful when stitching together superposed plies of unlike material, as a ply of relatively heavy unyielding material and a ply of relatively light yielding material.

It is a further object of the invention to provide a supplemental feeding mechanism which is adapted to be readily associated with and driven by a conventional sewing machine.

Another object of the invention is to provide a supplemental feeding device involving upper and lower positively driven rollers and in which the driving mechanism for the upper roller is entirely clear of the work plate over which the material is fed.

An important feature of the invention, therefore, resides in the provision of a supplemental

feeding device involving an upper feed roller and a lower feed roller which are both positively driven through separate clutches.

Another feature of the invention resides in the provision of an advantageous construction to guard against any tendency of the material being drawn beneath the work plate by the lower roller.

Another feature of the invention resides in the provision of a novel driving connection between upper and lower feed rollers, involving a clutch connected to the upper roller, which is operatively connected to a clutch connected to the lower feed roller.

A further feature of the invention resides in the provision of an advantageous driving connection between cooperating upper and lower feed rollers, whereby the rate of feeding movement of one of the rollers may be varied with respect to that of the other roller.

Another feature of the invention resides in the operative association with a stitching mechanism and a main feeding mechanism of cooperating upper and lower feed rollers which are adapted to be positively driven coordinately with the main feeding mechanism and which are adapted to be driven at different rates of feed relative to each other and relative to the main feeding mechanism.

Other objects, features and advantages will hereinafter appear.

In the drawings which illustrate a present preferred embodiment of the invention:

Fig. 1 is a rear view of a feeding device embodying the present invention, certain of the parts being broken away to enable a more clear illustration.

Fig. 2 is an end view showing the feeding device illustrated in Fig. 1, in operative combination with a sewing machine.

Fig. 3 is a sectional view taken on the line 3—3 of Fig. 1 and like Fig. 2 showing the feeding device in operative combination with a sewing machine.

Fig. 4 is a detail partial sectional view taken substantially on the line 4—4 of Fig. 2.

Before describing the present improvements and mode of operation thereof in detail it should be understood that the invention is not limited to the details of construction and arrangement of parts shown in the accompanying drawings, which are merely illustrative of the present preferred embodiments, since the invention is capable of other embodiments, and the phraseology employed is for the purpose of description and not of limitation.

Referring more particularly to the drawings there is shown for the purposes of illustration a sewing machine 11 which, as disclosed in the drawings, may be of the well-known Metropolitan type, including a lower arm 12 above which is supported an upper or overhanging arm 13 carrying a sewing head 14 in which is mounted in a well understood manner a needle bar 15 carrying a needle 16 for cooperation with a looper 17, and a presser bar 18. A presser foot 19 on the presser bar 18 is adapted to cooperate with a feed dog 20 which may be part of a usual four-way main feeding mechanism operated in a conventional manner from a main drive shaft 21 in the lower arm of the sewing machine.

It is for the purpose of providing an improved supplemental feeding device 22 for use in combination with the stitching and feeding mechanism of a sewing machine, such for example as the sewing machine 11 briefly described above, that the present invention is primarily directed.

As shown, this supplemental feeding device 22 comprises a main frame 23, which may be of the same general C-shape as the main frame shown in Patent 1,736,297 to correspond with the general shape of the frame of the illustrated sewing machine, including a base or lower arm 24 with an upstanding support 25 at one end from which extends an upper or overhanging arm 26. Supported in bearings 27, 28 and 29 within the lower arm 24 is a shaft 30 on which and between the bearings 27 and 28 is mounted a lower roller feed means 31.

Preferably and as shown this lower roller feed means 31 is divided into a plurality of rollers 32, 33 and 34 fixed to the shaft 30 and spaced slightly axially of each other to provide spaced roller feed surfaces 35, 36 and 37 adapted to extend upwardly through an opening 38 formed in a work plate 39 which may be secured to the lower arm 24 as by screws 40. Advantageously supporting strips 41 and 42 are formed on the work plate to extend across the opening 38 in the spaces between adjacent feed surfaces of the lower roller feed means and thus divide the opening into a plurality of feed surface receiving apertures. This provision of a plurality of feed surfaces 35, 36 and 37 with supporting strips 41 and 42 therebetween is particularly helpful in overcoming any tendency of the work being adversely fed beneath the work plate as it is directed toward and away from the feed surfaces.

Also, it is to be noted that while the forward marginal edge portion 43 of the work plate is substantially flush with the main surface 44 of the top of the lower arm, the portion 45 of the work plate surrounding the feed opening 38 is offset slightly downwardly. In this manner, the work is directed to the feed means in a particularly advantageous manner.

Supported for up and down sliding movement in bearings 46 and 47 at the free end of the upper arm 26 is a presser bar 48 having secured to the lower end thereof, as by a set screw 49, a yoke member 50. Fixed to a shaft 51 mounted in bearings in depending arms 54 and 55 of the yoke member is a roller 56, cooperable with the lower roller feed means 31 and constituting the upper roller feed means 57. The work gripping surfaces of the upper and lower feed means may be of any suitable construction, but as illustrated the lower feed surfaces 35, 36 and 37 are knurled and the surface 58 of the upper roller is advantageously of rubber or rubberlike composition.

As in the case of the feeding device shown in Patent 1,736,297, a spring strip 59 may be utilized for normally urging the upper roller means 57 toward the lower roller means 31 with yielding pressure, and a pivotally mounted lever arm 60 engageable under a guide block 61 on the presser bar 48 is provided for raising the upper roller means.

Of particular importance, however, there is provided by the present invention as advantageous means by which both the upper and lower roller feed means are positively driven and by which the work advancing movement of one roller means 57 may be varied with respect to that of the other roller means 31.

Thus, as shown, there is mounted on an extension of the upper roller shaft 51 a one-way clutch 62 which as is conventional may include a member 63 having a hub portion 64 fixed to the shaft 51 and formed with a shell 65 into which fits the driving section 66 of a member 67 which is rotatable on the shaft. Spring pressed rollers 68 located in wedge-shaped peripheral recesses 69 in the driving section are adapted to be moved into wedging contact with the shell 65 when the member 67 is rotated in one direction and to be disengaged from wedging contact with the shell 65 when the member 67 is rotated in the other direction. In this manner, oscillating movement of the member 67 serves in a well-known manner, for example as described in Patent 1,946,514 granted to John P. Weis on February 13, 1934, to rotate the shaft 51 in a step-by-step movement. This movement is, of course, transmitted to the upper feed roller 56.

Extending from the face plate 70 of the member 67 is a rocker arm 71 having a longitudinal slot 72 formed therein to receive a slide member 73 having a flange 74 at one side thereof adapted to engage one side of the rocker arm and having a hub portion 75 adapted to fit in a bearing 76 at one end of a connecting link 77. A headed screw 78 passing through a threaded bore in the slide member 73 and having a washer and nut 79 thereon at one side of the rocker arm 71, serves to lock the slide member 73 and link 77 at a selected position on the rocker arm. It will be readily appreciated that by moving the slide member longitudinally of the slot, the effective lever length of the rocker arm may be varied and in this manner the extent of rotating movement imparted to the upper feed roller 56 by movement of the link 77 may be controlled.

For rotating the lower shaft 30 and lower roller feed means 31 in a step-by-step movement concurrently with the operation of the stitching mechanism and main feeding mechanism of the sewing machine 11, there may be and preferably is, as shown, provided a clutch unit 80 on an extension of the lower drive shaft 30. Advantageously this clutch unit is so organized that not only is there a means provided for effecting a step-by-step advance of the lower roller feed means in one direction, but there also is provided a means to insure movement of the lower shaft 30 and associated roller means 31 in only that one direction.

This clutch unit 80 is a combination of two clutches 81 and 82 substantially identical with the clutch 62 above described and involves a centrally disposed member 83 with a hub portion 84 fixed to the shaft 30 and spacing shell portions 85 and 86 adapted to receive roller carrying sections 87 and 88 of members 89 and 90 similar in construction to the member 67 of the

clutch 62, having respectively spring pressed rollers 91 and 92 positioned in wedge-shaped recesses 93 and 94 and adapted to wedgingly engage the respective confining shells 85 and 86. A face plate 95 on the member 89 is maintained 5 against turning with the shaft 30 by a pin 96 extending from the base 24 of the main frame into a slot 97 formed in a projecting arm 88 on the face plate 95. On the other hand, however, a face plate 99 on the member 89 is adapted for oscillating and rotating movement on the shaft 30. With this construction oscillation of the face plate 99 causes the wedging action of the spring pressed rollers 91 to rotate the shaft and lower roller feed means 31 carried thereby in a step-by-step movement in one direction while the wedging action of the spring pressed rollers 92 locks the shaft 30 and lower roller feed means 31 against rotation in the opposite direction. A clutch unit which operates substantially in the 20 manner of the clutch unit 80 is illustrated and described in Patent 2,095,647 granted to Joseph Mann on October 12, 1937.

Of importance, attention is directed to the fact that there are two lever sections 100 and 101 extending from the face plate 99 of the clutch unit 80. As in Patent 1,736,297, one lever section 100 has secured thereto a ball stud 102 which is adapted to be received in a ball socket 103 at one end of a rod 104, the other end of which is pivotally mounted on a pivot pin 105 of an adjustable eccentric 106 mounted on a main drive pulley 107 on the lower drive shaft 21 of the sewing machine. This eccentric 106, consists of a key 108 which is slidably mounted within a keyway 109 in the hub 110 of the pulley 107 and to which is secured the pivot pin 105. A screw 111 is mounted for rotary movement only within the solid wall portion 112 of the hub 110 and is threaded into the key 108. By loosening nut 113 and turning screw 111 in one or the other direction, the pivot pin is shifted to vary its eccentricity relative to the axis of the drive shaft 21. In this manner the extent of rocking movement of the lever section 100 and the degree of advance of the lower feed means 31 can be varied independently of the main feeding mechanism of the sewing machine.

Of importance, connected to a pivot screw 114 secured to the other lever section 101, is one end 50 of a link 115, the other end of which is secured to a pivot stud 116 secured to a lever arm 117 clamped to one end 118 of a rock shaft 119 carried by the upper arm. Advantageously and as shown, the rock shaft is mounted in bearings 120 and 121 fixed to the main frame and extends longitudinally of the upper arm 26 entirely clear of and spaced upwardly from the lower arm 24 and work plate 39. At the other end 122 of the rock shaft 119 there is clamped another lever arm 123, similar to the lever arm 117, and to which, as by a pivot stud 124, is connected the link 117 which is adjustably connected to the rocker arm 71 of the driving clutch for the upper roller 56.

With the construction above described it will be readily apparent that by adjusting the eccentric 106 on the drive shaft 21 of the sewing machine, the rate of feed of the upper and lower roller feed means may be varied relative to that of the main feeding mechanism of the sewing machine; by shifting the link 117 relative to the rocker arm 71 the rate of feed of the upper roller feed means 51 may be varied with respect to that of the lower roller feed means 31 and 75

with respect to that of the main feeding mechanism of the sewing machine; and a simple and effective means is provided for driving both the upper and lower roller feed means coordinately and in selected timed relation with respect to that of the main feeding mechanism of the sewing machine.

Variations and modifications may be made within the scope of this invention and portions of the improvements may be used without others.

Having thus described the invention, what is claimed as new is:

1. In a device of the character described, the combination of a first roller feeding means; a second roller feeding means; means for supporting said first and second roller feeding means in vertically opposed relation for cooperative feeding movement; means for operating said second feeding means; and means for connecting said operating means with said first roller feeding means for conjoint operation with said second roller feeding means, said connecting means including as a part thereof relatively movable elements relatively movable into divers positions of adjustment relative to each other for varying the relative rate of feed of said first and second roller feeding means.

2. A device of the character described, comprising a lower roller feed means; an upper roller feed means; means for supporting said upper and lower roller feed means for cooperative feeding movement; a first clutch connected to said upper roller feed means; a second clutch connected to said lower roller feed means; a first lever means on said second clutch for rotating the lower roller feed means; a second lever means on said second clutch, movable by and with said first lever means; and means connecting said second lever means and said first clutch for conjoint rotation of said upper and lower roller feed means.

3. A device of the character described, comprising a lower roller feed means; an upper roller feed means; means for supporting said upper and lower roller feed means for cooperative feeding movement; a first one-way clutch connected to said upper roller feed means; a second clutch connected to said lower roller feed means; a first lever means on said second clutch for rotating the lower roller feed means; a second lever means on said second clutch, movable by and with said first lever means; a rocker arm on said first clutch; a link connected to and movable longitudinally of said rocker arm for varying the effective length of the latter; and means connecting said link to said second lever means for conjoint operation of said upper and lower roller feed means.

4. A device of the character described, comprising a main frame having a base; a lower roller feed means supported relative to said base and having an axis of rotation, said lower feed means including a plurality of rollers spaced from each other longitudinally of said axis of rotation; a work plate on said base, having a first portion forwardly of said axis of rotation and having a second portion downwardly offset relative to said first portion and overlying said axis of rotation, said second portion being formed with a plurality of apertures with work supporting means therebetween, said apertures being respectively aligned with said rollers and said rollers extending upwardly through said apertures; upper roller feed means supported over said work plate, for cooperation with said lower roller feed means; and

means for positively rotating at least one of said roller feed means.

5. In a device of the character described, the combination of lower roller feed means; upper roller feed means; means for supporting said lower and upper roller feed means for cooperative feeding movement; operating means for positively driving both of said roller feed means and operatively connected to each of the same, said operating means including a link and lever adjustably connected to each other and operatively interposed between said upper and lower feed means for varying the rate of feed of said upper and lower feed means relative to each other.

6. In combination with a sewing machine having a stitching mechanism and a main feeding mechanism, a lower roller feed means; an upper roller feed means; means for supporting said upper and lower roller feed means for cooperative feeding movement; operating means operatively connected to said main feeding mechanism and to each of said upper and lower rollers, for effecting coordinate operation of said main feeding mechanism and said upper and lower roller feed means, said operating means including means as a part thereof for varying the rate of feed of said upper and lower roller feed means relative to each other and relative to said main feeding mechanism.

7. In a device of the character described, the combination of a main frame having an upper arm and a lower arm; a work support on the lower arm; an upper feed roller supported by said upper arm; a lower feed roller supported by said lower arm, cooperable with said upper feed roller; and means for positively driving each of said rollers and operatively connected to each of the same, said means including a link and lever adjustably connected to each other and operatively interposed between said upper and lower rollers for varying the rate of feed of said upper and lower rollers relative to each other.

8. An auxiliary feeding device for association with a sewing machine, comprising lower roller feed means; upper roller feed means; means for supporting said upper and lower feed means for cooperative feeding movement; a first one-way clutch for said lower feed means; a second one-way clutch for said upper feed means; means on said first clutch for effecting an operating connection with an associated sewing machine; lever means on said first clutch, movable by and conjointly with said last-named means; and means for operatively connecting said lever means and said second clutch, said connecting means including an adjustable means on said second clutch for varying the advancing movement of the upper roller feeding means relative to the lower roller feeding means.

9. In a device of the character described, the combination of a main frame having an upper arm and a lower arm; a work support on the lower arm; an upper feed roller supported by said upper arm; a lower feed roller supported by said lower arm, cooperable with said upper feed roller; a rock shaft extending longitudinally of and supported by said upper arm entirely clear of and spaced above said work support; a one-way clutch connected to the upper feed roller; a rocker arm on said clutch; means for positively rotating said lower roller with a step-by-step movement; means including a lever for connecting said last-named means to said rock shaft; and means for connecting said rock shaft to said

rocker arm for conjoint operation of said upper and lower rollers.

10. In a device of the character described, the combination of a main frame having an upper arm and a lower arm; a work support on the lower arm; an upper feed roller supported by said upper arm; a lower feed roller supported by said lower arm, cooperable with said upper feed roller; a rock shaft extending longitudinally of and supported by said upper arm entirely clear of and spaced above said work support; a one way clutch connected to the upper feed roller; a rocker arm on said clutch; means for positively rotating said lower roller with a step-by-step movement; means including a lever for connecting said last-named means to said rock shaft; and means for connecting said rock shaft to said rocker arm, including means moveable longitudinally of said rocker arm to vary the step-by-step movement of the upper roller relative to that of the lower roller.

11. A device of the character described, comprising a main frame having an upper arm and a lower arm; a lower roller feed means supported by said lower arm; a cooperating upper roller feed means; means supporting said upper roller feed means on said upper arm for movement toward and away from said lower roller feed means; a first one-way clutch means for operating said lower roller feed means; a second one-way clutch means separate from said first one-way clutch means, for operating said upper roller feed means; means for actuating one of said one-way clutch means to effect a step-by-step rotation of the roller feed means operated by the latter; and means interconnecting said first and second one-way clutch means for conjoint step-by-step rotation of said upper and lower roller feed means.

12. In a device of the character described, the combination of a main frame having a lower arm providing a work support, and an upper arm spaced upwardly therefrom; a first feeding means supported by said upper arm; a second feeding means supported by said lower arm, and having a portion extending upwardly relative to said work support for cooperation with said first feeding means; a first drive shaft for said first feeding means, supported by said upper arm entirely clear of and spaced above said work support; a first one-way clutch operatively connecting said first drive shaft and said first feeding means; a second one-way clutch operatively connected to said second feeding means; lever means on said second clutch for operating the same; and link and lever means connecting said second clutch and said first drive shaft for conjoint operation of said first and second feeding means.

13. In combination with a sewing machine having a stitching mechanism and a feeding mechanism, an auxiliary feeding device comprising a main frame having an upper and a lower arm; cooperable upper and lower roller feeding means respectively supported by said upper and lower arms in feeding alignment with and rearwardly of said sewing machine feeding mechanism; means interconnecting said upper and lower roller feeding means for positive conjoint operation, said interconnecting means including means for varying the feeding movement of said upper and lower feeding rollers relative to each other; and means connecting said auxiliary feeding device and said sewing machine for operating said roller feeding means with said feeding mechanism.

14. A device of the character described, com-

prising a main frame having an upper arm and a lower arm; a work plate on said lower arm; a lower roller feed means supported by said lower arm; a cooperating upper roller feed means; means supporting said upper roller feed means on said upper arm for movement toward and away from said lower roller feed means; a first clutch means for operating said lower roller feed means; a second clutch means for operating said upper roller feed means; a rock shaft extending longitudinally of and supported by said upper arm, entirely clear of and spaced upwardly from said work plate and said lower arm; means for transmitting rocking movement to said rock shaft from said first clutch means; and means for transmitting rocking movement from said rock shaft to said second clutch means.

15. A device of the character described, comprising a lower roller feed means; an upper roller feed means; means for supporting said upper and lower roller feed means for cooperative feeding movement; a first clutch connected to said upper roller feed means; a second clutch connected to said lower roller feed means; a first lever means on one of said clutches for rotating the roller feed means to which said one of said clutches is connected; a second lever means on said one of said clutches, movable by and with said first lever means; and means connecting said second lever means on said one of said clutches and the other of said clutches for conjoint rotation of said upper and lower roller feed means.

16. A device of the character described, comprising a lower roller feed means; an upper roller feed means; means for supporting said upper and lower roller feed means for cooperative feeding movement; a first clutch connected to said upper roller feed means; a second clutch connected to said lower roller feed means; actuating means on one of said clutches for rotating the roller feed means to which said one of said clutches is connected; lever means on said one of said clutches, movable by and with said actuating means; and means connecting said lever means on said one of said clutches and the other of said clutches for conjoint operation of said upper and lower roller feed means.

17. In a device of the character described, the combination of a lower feed roller; an upper feed roller; means for supporting said upper and lower feed rollers for cooperative feeding movement; means for positively rotating one of said feed rollers with a step-by-step movement; a one-way clutch means connected to the other of said feed rollers; and means for operatively connecting said last two-named means for conjoint operation, said connecting means including an adjustable means for varying the advancing movement of one of said feed rollers relative to the other of said feed rollers.

ALBERT H. WEIS.
